UNITED STATES PATENT OFFICE.

DANIEL BEST, OF SAN LEANDRO, CALIFORNIA,

GAS-ENGINE.

SPECIFICATION forming part of Letters Patent No. 484,727, dated October 18, 1892.

Application filed June 10, 1891. Serial No. 395,811. (No model.)

To all whom it may concern:

Be it known that I, DANIEL BEST, a citizen of the United States, residing at San Leandro, Alameda county, State of California, have invented an Improvement in Gas-Engines, and I hereby declare the following to be a full, clear, and exact description of the same.

My invention relates to certain improvements in engines which are propelled by the explosion of an inflammable vapor or gas and in which the piston moving in the engine cylinder first serves as a pump to draw a charge of the explosive gas or vapor into the cylinder and after returning to compress the vapor in the end of the cylinder is again propelled to the opposite end of the stroke by the ignition and explosion of the confined vapor.

It consists in details of construction, which will be more fully explained by reference to the accompanying drawings, in which—

Figure 1 is a side elevation of my machine. Fig. 2 is an end view, the cylinder-head being removed. Figs. 3 and 4 are details illustrating the two positions of the electrodes.

25 A is the cylinder of my engine.

B is the crank-shaft.

A piston is fitted to reciprocate within the cylinder and has a piston-rod, a slide traveling upon guides, and a connecting-rod extending 30 between said slide and the crank upon the shaft B, this being of the usual construction by which a rotary motion is communicated to the crank-shaft.

D is a pipe leading from the reservoir containing the gas or vapor or the material from 35 which it is generated.

E is a valve, which in the present case is of the form known as "puppet-valve," and which is kept closed by means of a spring F, 40 surrounding its stem and holding it down upon its seat with a sufficient tension to prevent the passage of the gas or vapor except when all other passages or openings into the cylinder are closed and the piston is moving toward the front end of the cylinder. At such 45 times the vacuum produced in the cylinder by the movement of the piston is sufficient to overcome the tension of the spring F and allow the vapor or gas to pass through the 50 valve and into the cylinder.

G is the exhaust pipe or passage. (Shown in the present case upon the opposite side of the

cylinder from the inlet-pipe and connecting, as in the former case, with the cylinder near its rear end.)

55

H is a puppet valve, which closes the exhaust-opening, this valve being held down upon its seat by a spring I, which keeps it closed when it is not otherwise acted upon. When this valve is kept open, it will be manifest that when the engine is running the reciprocations of the piston will simply draw air in through the exhaust-pipe G and force it out again, the valve E, which supplies the explosive vapor, remaining closed at all such 60 times. If, however, the valve H is temporarily closed, it will be manifest that the movement of the piston will draw a charge of explosive vapor through the pipe D and valve E into the cylinder, and the return of the piston while the valve H is still closed will compress this gas between the piston and the end of the cylinder in the usual manner, and it is then exploded by an electrical device or ignitor, which will be hereinafter described. 65 The valve H is then again opened to allow the exhaust of the waste products, and if the engine is running at too high a rate of speed it will remain open and nothing but air will be pumped into the cylinder and forced out again until the speed of the engine is reduced 70 sufficiently to allow the spring to again close the valve H after it is released from the governing mechanism.

The mechanism by which this valve is actuated is driven directly from the main shaft B, as follows: Upon the shaft B is fixed a pinion J, and this engages with a corresponding-toothed gear-wheel K, the diameter of which is such that the gear-wheel will make 75 one revolution to each four strokes of the piston and corresponding revolutions of the engine-shaft. Upon the shaft L of this gear-wheel is fixed a double cam M, which revolves with the shaft.

N is a connecting-rod having an antifrictional roller O journaled at the rear end and projecting to one side, so as to stand in line with the cams M, and when the rod is drawn into position so that the cams will engage the roller it will be moved backward at each contact with the cams, there being two of the cam-points situated at opposite sides. It will be seen that under these conditions the con- 85 90 95

necting-rod N will be moved by the cams at each half-revolution of the shaft L and gear K and at each second revolution of the engine-shaft. The connecting-rod N has its opposite end united with one arm of the bell-crank lever P, which is fulcrumed, as shown at Q. The other arm P' of this lever stands just beneath the stem I' of the valve H, and it will be manifest that the reciprocation of the connecting-rod N, produced by the action of the cams M, will be communicated to the bell-crank lever P P', and through it will act upon the valve-stem I', and at each movement will temporarily open the valve H, allowing the spring to close it again as the cams release the connecting-rod. The slot in the rod N is of sufficient diameter to allow the shaft L to pass through it, and in the present case it serves as a guide, allowing the connecting-rod N to be reciprocated by the action of the cams; but I do not limit myself to this construction. When the engine is running slowly or at its normal speed, the valve H being closed at the instant when the piston commences to move from the rear end of the cylinder, the piston will draw in a charge of gas or explosive vapor through the valve E, the vacuum produced by its movement overcoming the tension of the closing-spring F, as before described. As the piston makes two reciprocations while the cam-shaft L is making a half-revolution, it will be manifest that the exhaust-valve will remain closed until the piston has returned and compressed the charge which has been drawn into the end of the cylinder. At the instant when the piston is ready to commence another stroke the electrical ignitor acts to ignite the charge and its explosion forces the piston to the end of its stroke. At this instant the exhaust-valve is opened by the action of one of the cams M and the waste products of combustion are discharged by the return of the piston to the rear end of the cylinder, the valve being instantly closed again by the action of the spring I as soon as the connecting-rod N is released from the cam which has opened it. This operation continues as long as the engine is running within the speed to which it is normally adjusted; but whenever it runs at too high a rate of speed the operation of the cams upon the valve is arrested in such a manner as to hold the exhaust-valve open and allow air to be pumped in and forced out again by the movement of the engine-piston while the supply-valve at E remains closed. This control is effected by a governor R, which may be of any suitable or desired construction. Its stem connects with a pivoted swinging or movable arm S, one end of which is fulcrumed at T so that the arm moves about the fulcrum and the other end is adapted to engage a lug U, which projects from the reciprocating rod N. When the engine is running loosely, the point of the pawl S is raised above the lug U and the reciprocation of the rod N and its connected parts is regularly produced by the action of the cams M, before described; but whenever the speed of the engine becomes too great the action of the governor pushes down the point of the pawl S until it engages the lug U. The position of this lug is such that when it is drawn back far enough to be engaged by the point of the pawl S the connecting-rod N will be held in such a position that the cams M cannot engage the roller O, and consequently no reciprocation of the rod N will occur, and the valve H will be held open by the action of the bell-crank lever upon its stem. This valve being held open, it will be manifest that air will be free to flow through the exhaust-pipe G, moving in and out with the reciprocations of the engine-piston, and as no explosive gas is admitted while this takes place the speed of the engine and the governor will gradually be reduced and the pawl S raised until it is free of the lug U, when the spring I on the valve-stem I' will again act to close the valve H, at the same time drawing the connecting-rod N back to the point where the roller O may be engaged by the cams M and the valve again operated in conjunction with the movements of the piston, so as to allow explosive vapor to be drawn in through the supply-valve. By this construction and the novel control of the exhaust instead of the supply valve I am enabled to regulate the speed of my engine with great nicety and cause it to run with great steadiness.

In order to ignite the charge of vapor which is admitted into the engine, I may employ any suitable form of electrical spark-producing device. In the present case I have shown a post *a* extending into the cylinder and having a point *b* projecting from one side. This point is insulated from the cylinder and is connected with one of the conducting-wires from a battery conveniently situated with relation to the engine. The other conducting-wire is connected with an oscillating shaft *c*, extending into the cylinder and similarly insulated from it. This shaft is caused to oscillate by means of an arm *d*, one end of which is fixed to the shaft and the other connected with a rod *e*. This rod *e* is connected with a crank upon the gear-wheel K, and is thus caused to reciprocate in unison with the revolutions of the gear K. As the gear K makes one revolution to four of the crank-shaft, it will be seen that this rod and its connecting devices will be reciprocated in each direction at every second revolution of the crank-shaft, these revolutions conforming to the admissions of the gas or explosive vapor into the cylinder. In order to produce a spark at each of these movements, I affix to the upper end of the shaft *c* a warped blade *f*, the end of which projects toward the projecting pin *b*. This blade is made elastic and is twisted, so as to stand at an angle, like a propeller-blade. It will be manifest that when the reciprocation of the connecting-rod and the oscillation of the shaft *c* causes the blade *f* to strike the pin *b* a spark will be produced.

lation of the shaft C carries this blade in one direction its front edge will pass above the pin B, and its elasticity will allow it to move over the pin until its opposite edge passes the pin, producing a spark at that instant by breaking the connection through the battery and wires. When the shaft C oscillates in the opposite direction, the lower edge of this inclined elastic plate will pass beneath the pin b, and as the upper edge leaves the pin a spark will again be produced. By this construction I am enabled to produce a spark for the ignition of the gas at each second revolution of the crank-shaft and at each end of the reciprocation of the rod, which is actuated by the gear-wheel K.

It has been found that the best results of a gas-engine are produced when the explosive mixture is ignited at the instant of greatest compression and as the crank passes the center nearest the cylinder and the piston is ready for the outward stroke. If the piston starts on its stroke before the ignition, the compression is reduced and a great loss of energy is observable. When the engine is started and the parts are cold, it is necessary that the points of the electrical ignitors should be in the proper relation to explode the gas at the proper time; but when they become heated and elongated, if they are in line with each other, as in the case of rotary or oscillating wipers, the elongation causes them to break the connection so much later that the piston will have made a portion of its stroke before the explosion of the gas, and much power is lost. By my arrangement the stationary pin and the inclined propeller-like blade overlap or extend beyond a meeting-point, so that the edges of the blade and the sides of the pin engage with each other and no amount of longitudinal extension or contraction by heat or cold will alter the time of making the spark and the explosion of the charge.

Having thus described my invention, what I claim as new, and desire to secure by Letters Patent, is—

1. An igniting device for a gas-engine, con-

sisting of opposing fixed and movable electrodes whose meeting ends overlap, one of said electrodes being formed of a warped 50 elastic plate adapted to yield upon contact with the opposing electrode and to sweep across the upper and lower surfaces of the said opposing electrode in planes transverse of its line of projection.

2. In a gas-engine, the electrical igniting device consisting of a stationary insulated pin or finger connected with one of the electrodes, an insulated shaft with mechanism connecting it with the engine-shaft, whereby 60 it is oscillated, and an elastic plate having a warped surface fixed to the inner end of said shaft and projecting toward and in line with the opposing electrode and beyond the plane of its end, whereby said elastic plate 65 is adapted to sweep across the overlapping end of the opposing fixed electrode in planes at right angles to the line of projection of the fixed electrode on one of its oscillations and to return in like manner across the opposite 70 face of the fixed electrode on the reverse oscillation, substantially as herein described.

3. In a gas-engine, a cylinder, reciprocating piston, crank-shaft, an inlet-valve through which the explosive mixture is drawn by the 75 movement of the piston, an independent spring-closed exhaust-valve, a cam-shaft and intermediate mechanism and a governor by which the exhaust-valve is opened and its movements regulated, an ignitor consisting of 80 a fixed and an oscillating electrode, a crank upon the cam-shaft, and connections, substantially as described, between it and the movable electrode, and gearing upon the cam-shaft and the main engine shaft, whereby the exhaust-valve is opened and a spark produced by the ignitor at each second revolution of the main shaft.

In witness whereof I have hereunto set my hand.

DANIEL BEST.
